UNITED STATES PATENT OFFICE.

WILLIAM H. EMERSON, OF DETROIT, MICHIGAN.

GRAIN-RIDDLE.

No. 861,446.

Specification of Letters Patent.

Patented July 30, 1907.

Application filed January 4, 1907. Serial No. 350,764.

To all whom it may concern:

Be it known that I, WILLIAM H. EMERSON, a citizen of the United States, residing at Detroit, in the county of Wayne and State of Michigan, have invented certain 5 new and useful Improvements in Grain-Riddles, of which the following is a specification.

This invention relates to grain riddles and has for its object to provide an improved riddle especially adapted for separating oats from other grain, particularly from round-berried grain.

The riddle is constructed without wood, which is subject to deterioration or warping, and it is also intended to be constructed in such manner that grain will not clog or stick therein.

15 The invention is illustrated in the accompanying drawings, in which

Figure 1 is a top plan view of a section of the riddle. Fig. 2 is a section on the line 2—2 of Fig. 1. Fig. 3 is a plan view of one of the blanks forming the spacing 20 and dividing plates.

Referring specifically to the drawings, 6 indicates the side piece and 7 the end piece of the frame work of the screen, which may be of any ordinary construction suitable for holding the screen body.

25 At 8 are indicated strips of metal equal in length to the space between the side bars or other lengthwise bars of the screen frame, and these strips are arranged at an inclination with respect to their width, the upper or higher edge of one strip extending above or beyond 30 the lower edge of the adjacent strip. Extending downwardly from each of the strips 8 is another strip of metal 9, the upper edge 10 of which is slightly bent, lengthwise, at a small angle to the remainder of the strip, as indicated at 10^a. The part 10 is arranged at 35 substantially a right angle with respect to the strip 8, the lower portion of the strip 9 extending at a more acute angle with respect to the top strips 8 than the upper portion 10, in consequence of the lengthwise bend referred to. The purpose of the bend is to avoid 40 the sharp corner where the strips join, in which grain berries might stick.

The upper strips 8 and lower strips 9 are held together, and also spaced in proper position with respect to each other, by means of a considerable number of 45 small division and spacing plates, indicated at 11. These plates are set edgewise between the series of strips comprised in the riddle, and the plates are shaped to preserve the angularity of the respective strips and also to bind the same together. The plates 50 11 stand edgewise, the upper edge 12 thereof being at an angle to fit under the upper edge of each strip 8, and the inclined edge 13 at the lower end fits upon the lower strip 9, and the lower edge 14 fits upon the lower 55 part of the next or adjacent upper strip 8, the lower edge of said strip fitting against a shoulder 15 formed in the plate. Each of the spacing plates 11 also has

three tongues arranged to extend through slits formed to receive them in the cross strips 8 and 9, and to be bent over plates to hold the parts together. One tongue, 16, projecting from the edge 12, extends upwardly through a slot in the upper edge of the strip 8; another tongue, 17, projecting from the edge 13, extends through a slot in the lower strip 9, and the third tongue, 18, which projects from the lower edge 14 of the plate, extends downwardly through a slot in the lower edge of the next or adjacent strip 8.

There are a plurality of the division plates 11 located between the strips and they are spaced apart a sufficient distance to allow a berry or kernel of grain to enter therebetween, but nevertheless too close together to 70 prevent an oat berry from swinging around crosswise, and, as a whole, they form a large number of small angular passages through which wheat or other round berries will pass and fall through the screen, but which will not pass oats because the oats which enter the 75 passages necessarily enter endwise and will be stopped when they strike the lower angular strip 9; and when the riddle is vibrated the oats are readily jarred out of the passages and travel along the surface of the screen to the tail thereof. When the oats are in the passage 80 formed by the strips and the plates they lie substantially parallel to the angle or lateral inclination of the strips 8, consequently on shaking or jolting the riddle they will ride quite readily along the surface of one strip to the next, and thus gradually to the end of the 85 screen. At the same time any short or round grain will turn the angle in the passages and fall through the screen.

The riddle has advantages of cheapness of construction, as the strips 8 and 9 are readily rolled, cut and 90 punched, and the spacing plates 11 may be stamped out of sheet metal in large quantities, and the parts are assembled by fitting the tongues through the slits in the various strips and up-setting the tongues to fasten the parts together. This gives an all metal 95 construction without the use of solder.

I am aware that hitherto riddles have been constructed having a rounded or semi-circular passage around the lower edge or strips of plates forming the surface of the riddle. Such a riddle is shown in my 100 U. S. Patent No. 793571. I am also aware that riddles have been constructed with V-shaped plates or passages, such riddle being shown, for example, in U. S. Patent No. 91307; and I am also aware that riddles have heretofore been constructed with Y-shaped 105 plates, as shown, for example, in U. S. Patent No. 452065. The present invention has advantages over all of these. In the first two constructions referred to the oats, particularly short oats, have a tendency to assume a vertical position between the edge over 110 which they turn and the opposite rounded or angular walls, and when this takes place the oat cannot be

dislodged therefrom by the movement of the riddle, but it has to be picked out by a pair of tweezers or the like; in other words, clogging of the riddle occurs. In the last mentioned construction, that having the Y-shaped plates, the defect exists that there is a tendency for the nose or butt of the oat to become stuck in the angle, particularly with wild oats, so that the whiskers of the oat catch on the stem or lower edge of the Y. Inasmuch as this kind of riddle is used principally to separate wild oats from wheat, and inasmuch as the wild oat is whiskered at the tip or nose, a screen having the Y plates becomes clogged more or less. In my construction, however, the end or nose of an oat entering one of the passages or pockets will strike the part 10. It cannot stick in so wide an angle, nor will it pass the angle 10°, and therefore its end will rest against the part 10. And it is to be further noticed that the space between the strips 8 is considerably greater than the width of the part 10. In practice I have found it advantageous to make the width of the part 10—that is, the distance from the plate 8 to the bend 10° referred to—two thirty-seconds of an inch, and a distance between the plates 8—that is, the distance from the edge 12 to the edge 14—five thirty-seconds of an inch. The comparatively wide space so provided allows an oat resting in the angle 10° to be easily jolted out or dislodged, and the oat is, so to speak, bridged across between the angle 10° and the plate 8 with sufficient room above to be jolted out and to allow the whiskers of the oat to clear the lower or turning edge of the strip 8. On the backward stroke of the riddle, when the oat slides into the passage it lodges on its end and strikes at or about the angle 10° and slides or raises up on the part 10 and thus lifts clear of the lower edge of the plate 8 and, when the riddle goes forward, is thus discharged from the passage. This avoids the tight holding or clogging incident to riddles having the V-shaped passages and also avoids the clogging incident to oats

being caught in vertical position or partly turned 40 around the angle. Therefore the riddle will not become clogged either by the oats assuming the vertical position, or by the whiskers of the oats catching on the lower edge of the strips.

I claim:

45

1. In a grain riddle, the combination of a series of upper strips and lower strips arranged at an angle to each other and spaced apart, and a series of spacing plates located in said spaces and having tongues extending through and fastened to the respective strips.

50

2. In a grain riddle, the combination of a series of upper spaced strips and lower strips arranged at an angle thereto, said strips having slits therein, and a series of plates arranged edgewise in said spaces, and having shoulders against which the lower edge of the upper strips abuts and also having tongues extending through and fastened in the slits in each of its contacting strips.

55

3. In a grain riddle, the combination of a series of upper strips, lower strips joined to said upper strips at an angle thereto and extending downwardly therefrom, said lower strips being bent along their upper edges to form blunt corners at the angles, and division plates between said upper and lower strips, forming passages through the riddle.

60

4. In a grain riddle, the combination of a plurality of spaced overlapping upper strips, a plurality of lower strips attached thereto, each of the lower strips being bent lengthwise, and having an upper part joined at the edge to the under side of the upper strip at substantially a right angle thereto, and a plurality of division plates located 65 between said strips.

70

5. In a grain riddle, the combination of upper strips spaced apart, lower strips having a lengthwise bend forming an upper part at an angle thereto and secured along the under side of the upper strips at substantially a right angle thereto, the width of the said upper part being less than the space between the upper strips, and division plates between said upper and lower strips.

75

In testimony whereof I affix my signature, in presence of two witnesses.

WILLIAM H. EMERSON.
